UNITED STATES PATENT OFFICE.

WILLIAM R. EDSON, OF SOUTHBRIDGE, MASSACHUSETTS.

PICKER MAGNET.

Application filed January 6, 1927. Serial No. 159,365.

This invention relates to magnetic tools and has particular reference to an electro-magnetic tool for picking or removing fallen nuts, bolts and other steel particles from the mechanism of an automobile or other pieces of machinery or from places that are not easily accessible.

The principal object of the invention is to provide an improved magnetic picking tool that may be bent or deformed to reach around obstacles or into inaccessible places.

Another object of the invention is to provide a bendable magnet which may be readily deformed or bent to adapt its entrance into inaccessible places.

Another object of the invention is to provide such a picker magnet with a simple inexpensive handle that may be easily bent as desired to reach inaccessible places and also to form an opening and closing switch for electrically energizing or de-energizing the magnet.

Another object of the invention is to provide simple, inexpensive and efficient electromagnetic picker means adapted to be deformed to avoid obstacles and to reach inaccessible places.

Other objects and advantages of the invention will become apparent from the following specifications taken in connection with the accompanying drawings. It will be apparent that many changes may be made in the details of construction and arrangement of parts without departing from the spirit of the invention as falling within the accompanying claims, hence I do not wish to be bound to the exact details shown and described, the preferred forms only having been shown by way of illustration.

Referring to the accompanying drawings, Figure 1 is a top or plan view of the invention;

Figure 2 is a partial cross section on line 2-2 of Figure 1;

Figure 3 is a cross section on line 3-3 of Figure 1, and

Figure 4 is a cross section on line 4-4 of Figure 2.

Referring to the drawings in which corresponding reference characters denote corresponding parts throughout, Fig. 1 shows that the invention comprises a bendable magnet 1 made of soft bendable Norway iron, a bendable handle portion 2 which is a continuation of the magnet, and the current leads or wires 3 twisted around the portion 2.

Over the magnet 1 is wound the wire coil 4, Fig. 2, for energizing the magnet 1. Over the coil 4 is placed the insulation wrapping 5. The end of the magnet 1 is fashioned into a picker nose or face 6 adapted to pick up iron or steel objects when the magnet is energized. One of the leads 3 is attached to an insulated metallic rim 7 which fits over an insulating ring 20 surrounding the magnet, as shown in Fig. 2, and contacts with one end of the coil 4 around the magnet 1. The opposite end of the coil 4 is soldered at 19 to the magnet 1 and the other lead 3 is attached to a metallic band 8 fitting around an insulation ring 9, Fig. 3, which fits around the portion 2. The two leads 3 are attached to the source of electric current 10 at the posts 11 and 12 respectively. The end of the handle portion 2 is bent at 13 until the extension 14 beyond the bend lies substantially parallel with the main body of the portion 2.

To energize the magnet 1 the extension 14 of the portion 2 is pushed or bent in until it contacts with the metal ring 8, as indicated in dotted lines in Fig. 1. This completes one lead direct to the magnet through the portion 2. The other lead attaches directly to the coil 4 around the magnet 1, as has been described; hence when the contact is made at 8 the magnet 1 is energized. Both the magnet 1 and the handle portion 2 may be bent or deformed as desired to avoid obstacles between the operator and the object to be picked up. The tool is held in the hand of the operator at the bent portion 14. Electric energy may be furnished from a battery or other source of electric energy. When the magnet 1 is energized the picker face 6 will pick up iron or steel objects within the limits of its magnetic capacity by contacting the face 6 with the object to be picked up.

From the foregoing description it will be seen that I have provided simple, inexpensive and efficient means for withdrawing iron and steel objects from inaccessible places, which means are adjustable to avoid obstacles, and which provide a handy and easy operable tool for carrying out the objects of the invention.

Having described my invention, I claim:

1. An electro-magnetic tool comprising a pliable core formed of a single rod of soft flexible magnetic wire, a conductor coil wrapped around a portion of said core, an electric circuit means connected with the

conductor coil, one end of the core having a bent portion lying substantially parallel with the body of the core, and an exposed electrical contact point in the circuit associated with the body of the core and aligned with and spaced from the end of the bent portion of the core whereby the electrical circuit may be completed by pressing the end of the bent portion of the core against the exposed electrical contact point to energize the conductor coil and magnetize the portion of the core surrounded by the coil.

2. An electro-magnetic tool comprising a pliable core formed of a single rod of soft flexible magnetic wire, a conductor coil wrapped around the core adjacent one end thereof, electric circuit means connected with the conductor coil, one end of the core having a bent portion lying substantially parallel with the body of the core and an exposed electrical contact point in the circuit associated with the body of the core and aligned with and spaced from the end of the bent portion of the core whereby the electrical circuit may be completed by pressing the end of the bent portion of the core against the exposed electrical contact point to energize the conductor coil and magnetize the portion of the core surrounded by the coil.
3. An electro-magnetic tool comprising a bendable iron having one end finished into a picker nose and the other end bent until the terminal portion lies substantially parallel with the body thereof, a conductor coil

around a portion of the magnetic portion adjacent the picker nose having one end secured to the magnetic portion and the other to an insulated conductor plate supported by the magnetic portion, a second insulated conductor plate supported by the magnetic portion adjacent the bent end thereof, a pair of electric leads, one being attached to the first insulated plate and the other to the second insulated plate, an exposed contact point at the second insulated plate whereby the bent end of the magnetic portion may be pressed to contact with the contact point to close the circuit and energize the magnet.

4. An electro-magnetic tool comprising a bendable magnet portion of a single rod of soft magnetic iron having a hand portion which is a continuation of the magnet portion bent to be substantially parallel therewith, electric leads carried by the magnet portion, a conductor coil surrounding a portion of the magnet portion adjacent one end having one end secured to the magnet portion and the other to one of the electric leads, an insulated support on the magnet portion having an exposed contact point and aligned with the bent portion of the magnet portion and connected to the other electric lead whereby the circuit will be closed when the bent portion of the magnet portion is pressed against the contact point to energize the magnet portion surrounded by the conductor coil.

WILLIAM R. EDSON.
